EXPLOSION RIVET

Lawton A. Burrows, Woodbury, N. J., assignor to
E. I. du Pont de Nemours & Company, Wilming-
ton, Del., a corporation of Delaware

Application August 12, 1942, Serial No. 454,561

3 Claims. (Cl. 85—37)

This invention relates to the art of explosively blasting a contact between objects.

The present application is a continuation in part of my copending application Serial No. 274,771, filed May 20, 1939.

The original application discloses an explosive rivet charged with a detonating explosive capable of initiation by means of an electrostatic discharge of 100,000 ergs.

The object of the present invention is to apply this principle not only to explosive rivets but to any explosive metal connecting element. A further object is to apply the principle to fastening one or more articles. Additional objects will be disclosed in the following detailed description of the invention.

According to my invention a recess or perforation is formed in the article or articles to be joined or fastened and the metal fastening element is inserted in said recess. The metal fastening element contains a charge of a detonating explosive composition capable of initiation by means of a spark discharge including a high voltage, electrostatic discharge and the like.

When the joining, riveting, or fastening is to be performed, the explosive is ignited, preferably by means of an electrical conductor introduced into the cavity in the connector element such as a rivet, bolt or fastener and connected to a source of relatively high voltage electricity. This inserted electric conductor will desirably be insulated except at its terminal point. With this conductor sufficiently close to the bottom of the rivet, bolt, or connector cavity in the vicinity of the explosive charge, the circuit may be closed by the throwing of a switch, and a spark jumps across the gap between the conductor and the metal of the connector element or rivet, thereby bringing about the explosion.

In order to describe my invention more clearly, reference is made to the accompanying drawing. Figure 1 illustrates an "explosion" rivet in position for riveting together two metal sheets. Figure 2 shows the same rivet after the explosion. Figure 3 shows another design of explosion rivet before spreading, while Figure 4 illustrates the same rivet after expansion. Figure 5 represents a rivet of the countersunk type, after expansion, but otherwise similar to the one in Figure 4. Figure 6 shows an explosive bolt loaded with explosive according to my invention. Figure 7 shows a threaded explosive bolt already fired by means of a spark and expanded within a cavity in a metal plate according to my invention. Figure 8 shows an explosive electric cable connector

loaded with spark sensitive detonating explosive. Figure 9 shows an explosive electric connector element already fired by static means and thus expanded within a metal plate.

5 According to my invention, the connecting operation such as a riveting operation is carried out in the following manner. As shown in Figure 1, the shank 2 of the rivet is inserted through the drill hole in the two metal sheets 5 and 6 which are to be joined together. When in place, the head 1 of the rivet rests firmly against the nearest metal sheet. Within the cavity 3, in the shank of the rivet, a small charge is loaded of a detonating explosive capable of explosion by a spark discharge and very sensitive to such electric discharge. The explosion is brought about by introducing into the cavity a metal conductor connected to a source of high voltage electricity. The riveting effect will be apparent from Figure 2, where the bulging of the walls of the rivet shank is seen to have caused compression together of the metal sheets.

The rivet shown in Figure 1 was adapted to receive the explosive charge in a recess in the shank, opening at the base of the rivet. A different type of rivet is shown in Figure 3, which has a number of advantages over that previously described, and which is described in the copending case of Burrows and Lawson (Serial No. 274,772, filed May 20, 1939). In this type, the cavity within the rivet is made by boring or entering through the head 1. A relatively long and narrow cavity results. The explosive charge is shown at 2, and ignition is brought about by means of the insulated wire 7 which is connected with a source of high voltage electricity and which is introduced into the recess in the rivet and is caused to discharge a spark to the walls of said recess in the vicinity of the spark-sensitive explosive charge, when the circuit is closed. The bulging effect on the rivet walls is shown in Figure 4, and this is very effective in holding the two metal sheets tightly together. With either type of rivet it will be desirable that at least part 45 of the explosive charge in the rivet cavity be slightly beyond the surface of the metal sheet on the side opposite to the head of the rivet.

The same principle is shown in the remaining figures as applied to explosive bolts and electrical connectors. The electric discharge is applied to the explosive within the bolt or element which being susceptible to static is fired expanding the metal surrounding it to effect a tight junction. While my invention will be described particularly 55 with reference to riveting, it will be understood

that the principles apply as well to bolting, joining and fastening and connecting, as shown in these figures.

In the foregoing it is stated that a high voltage spark is utilized to bring about explosion. The explosive used according to my method is one which is capable of ignition by such a spark. I prefer to employ an explosive of the type which is sensitive to ordinary static effects, for example, lead styphnate, basic lead picrate, silver azide, copper acetylid, lead nitro-hypophosphite, and the like. These compounds can be detonated by static charges such as can readily be accumulated by a man of average capacity. Once initiated, also, they pick up to high velocity very rapidly; hence an extremely small amount of explosive will be effective. Since the explosive as used in my method of riveting is in a metal cavity, it is evident that there is no danger of static accumulation in the vicinity of the charge. The source of electricity for the firing spark will ordinarily be a condenser of suitable capacity, an induction coil, or regular power or lighting circuits where suitable transformers or other device have been introduced to give the desired control over the firing source. A difference of potential of around 2,000 volts and an energy output of a low order of magnitude are satisfactory conditions.

It is known that "explosion" rivets have been employed in the prior art. A preferred method of bringing about explosion has been by the application of heat to the rivet head. While such a method is effective, I find my method of spark ignition to have many advantages in the way of time-saving, convenience in operation, simplicity of equipment, and the like. When indirect heating is employed, a time lag of several seconds occurs between application of the heat and the moment of explosion; likewise, there is a loss of energy. In addition, the heating up of the metal sheets may be undesirable. With the spark ignition method of my invention, ignition is instantaneous, the energy is applied intensively, and only a very small amount of energy is required.

As shown in Figures 3 and 4 of the drawing, my preferred form of rivet has the entrance to the recessed cavity by means of a drill hole through the head of the rivet. With this type of rivet, my methods of loading and firing give an even greater advantage with regard to accessibility, since many rivets are used in positions where approach to the far side is difficult, if not impossible.

It has been stated in the foregoing that explosives of the type of lead styphnate are well suited for employment according to my invention, and compositions containing this compound as an ingredient are equally suitable. I find, for example, that a composition comprising 70 parts of lead azide, 20 parts of lead styphnate, and 10 parts of tetryl functions very satisfactorily. Other compositions are likewise adopted for use which are themselves readily spark-sensitive or contain an ingredient which is spark-sensitive and which, therefore, imparts this characteristic to the entire composition. Preferably, I employ an explosive charge which is capable of ignition by an electrostatic discharge of an energy amounting to 100,000 ergs, or less. This energy requirement is determined by a test in which a layer of the explosive of 0.010" thickness is spread on a steel plate and separated by a short gap from a steel needle. This needle is so ar-

ranged that it can be thrown into a closed circuit with a condenser of known capacity, on which a controlled voltage can be imposed. In this way a spark of the desired energy content can be caused to jump the gap from needle to plate at the locus of the explosive layer. Operating according to this arrangement, approximate electrostatic energy requirements in ergs for ignition of various explosives were determined as follows:

10	Lead styphnate	<500
	Copper acetylid	<500
	Lead nitro-hypophosphite	<500
	Lead azide (commercial)	>200,000

15 While the preferred compositions for use in rivets according to my invention have relatively low energy requirements for ignition, many other materials will be satisfactory for use having much higher requirements, though in all cases below 100,000 ergs.

20 The amount of explosive charge for satisfactory results will depend upon the nature of the explosive, the size of the rivet, and the material of which the rivet is constructed. With an aluminum rivet having a recess of $\frac{1}{16}$ " diameter, a 0.4 grain charge of a lead azide-lead styphnate composition may be satisfactory, whereas, with larger rivets and increased size of preformed cavity, a charge ten times as great may possibly be employed. Composite charges may likewise be used also, if desired, especially in the larger size rivets, for example, using in addition to the primary charge, a base charge of tetryl or other suitable material.

25 It will be understood that many different sizes of rivets may be employed according to my invention, depending on the type of work to be performed, and that such rivets may be of any of the common metals which have the properties of strength and malleability adapted to make them serviceable in such use. Copper, aluminum, and iron, and their alloys, may be cited as examples of suitable metals, though the use of copper and azides together is generally undesirable. While my invention has been directed to the joining of two metal sheets by means of rivets, it is apparent that more than two sheets may be joined in such manner, if desired.

30 In describing my process of riveting with use of explosive charges, it has been stated that the explosive is introduced into the bottom of the recessed cavity in the rivet. While we do not wish to be limited as to the method of introducing the explosive charge, my preferred method com-

35 prises extruding the charge into place in plastic form from a closed container, for example from a thin-walled collapsible tube. This method has the advantage of convenience and safety in handling the explosive composition. The extruded charge remains in place where deposited and hardens on subsequent evaporation of solvent. This hardening or setting requires a certain interval of time, hence the loading of the rivets will desirably take place previous to their insertion into the sheets to be riveted. Any of the explosive compounds mentioned as applicable can be handled and extruded in the manner described by treatment with the proper solvent to give the desired plasticity.

40 In the case of large rivets, or fasteners, it is desirable first to charge the explosive into a cylindrical metal shell and introduce this shell into a cavity in the connector prior to explosion.

45 A satisfactory method of preparing the explosive charge for extrusion and for obtaining the

desired viscosity is by blending with nitrocotton gelatinized by a suitable solvent.

My invention and method of riveting have been described at some length in the foregoing. It will be understood, however, that many variations may be made in details of procedure and design without departure from the scope of the invention. I wish to be limited only by the following patent claims.

I claim:

1. An explosive fastening element such as a bar, bolt, pin, rod, pipe or the like, wherein the element is provided with a central axial cavity extending from the end of said element within the same, and a detonating explosive charge capable of being ignited by an electric discharge of 100,000 ergs, disposed within said cavity, partly in that portion of the cavity adapted to extend within the object to be fastened, said cavity being open from the end of the element to the explosive charge.

2. An explosion rivet adapted to join at least two objects with surfaces in contact by being disposed in a hole extending through said objects, said explosion rivet comprising a metal rivet, a cavity extending longitudinally through the head and into the shank of said rivet, and a

detonating explosive charge capable of being ignited by an electrostatic discharge of 100,000 ergs disposed in said cavity, partly in that portion of the cavity in the shank of the rivet adapted to extend through and beyond said metal objects, and partly within that portion of said cavity in the shank positioned within the hole in said objects, said rivet being open from the head end to the explosive charge.

10 3. An explosion rivet adapted to join at least two metal objects with surfaces in contact by being disposed in a hole extending through said objects, said explosion rivet comprising a metal rivet, a cavity extending longitudinally through the head and into the shank of said rivet, and a detonating explosive charge comprising a static-sensitive explosive compound selected from the group consisting of lead styphnate, baric lead picrate, silver azide, copper acetylide, and lead nitroato-hypophosphite disposed in said cavity, partly in that portion of the cavity in the shank of the rivet adapted to extend through and beyond said metal objects, and partly within that portion of said cavity in the shank positioned within the hole in said objects, said rivet being open from the head end to the explosive charge.
